(57) **CLAIM**

The ornamental design for a formable cooler having a freezable gel in the walls for holding a juice box for placement in a child's lunch box, as shown and described.

DESCRIPTION

FIG. 1 is an isometric elevational view of a formable cooler having a freezable gel in the walls for holding a juice box for placement in a child's lunch box showing my new design; it being understood that the broken lines showing a juice box are for illustrative purposes only and form no part of my invention.

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.
